UNITED STATES PATENT OFFICE.

JOHN W. GILBERT, OF HILLIARD, OHIO, ASSIGNOR TO THE GILBERT MANUFACTURING COMPANY, OF COLUMBUS, OHIO, A CORPORATION OF OHIO.

MAIL CATCHER AND DELIVERER.

SPECIFICATION forming part of Letters Patent No. 733,025, dated July 7, 1903.

Application filed August 30, 1902. Serial No. 121,645. (No model.)

To all whom it may concern:

Be it known that I, JOHN W. GILBERT, a citizen of the United States, residing at Hilliard, in the county of Franklin and State of Ohio, have invented a new and useful Improvement in Mail Catchers and Deliverers, of which the following is a specification.

This invention is a combination mail-bag holder and deliverer, the object being to provide a device which can be used either for the purpose of holding a mail-bag to be caught by the railway mail-train or used as a catcher to receive and hold the mail-bag delivered from the train.

15 Another object of the invention is to provide a device which can be used as both a holder or deliverer and a catcher or receiver at one and the same time, so that one mail-bag can be held in position for the train and 20 at the same time the device can receive and hold a bag delivered from the train.

Another object of the invention is to provide a device of this kind which can be ready so as to operate in connection with trains 25 moving in either direction.

With these objects in view the invention consists of the novel features of construction, combination, and arrangement, all of which will be fully described hereinafter, and pointed out in the claims.

In the drawings forming a part of this specification, Figure 1 is a perspective view illustrating my invention adjusted for holding a mail-bag in position to be taken up by the train, said bag being shown in dotted lines. Fig. 2 is a detail perspective view showing a portion of the railway mail-car provided with my improvement and which is to be used in connection with the mail-bag holder shown in Fig. 1. Fig. 3 is a top plan view, partly in section, illustrating the main portion of the mail-bag holder and catcher. Fig. 4 is a detail view showing a portion of the combined holder and catcher. Fig. 5 is a detail view illustrating the manner of catching one mail-bag and delivering another at one and the same time, the caught bag being taken up by the train and the delivered bag being received and held by the holder. Figs. 50 6, 7, and 8 show detail perspective views of portions of the holder, and Figs. 9, 10, 11 are

detail views illustrating that portion of the invention carried by the mail-car.

In carrying out my invention I employ an upright frame A, comprising the face or sill A', upright portion A², and the top piece A³, and this frame is preferably arranged adjacent to the platform A⁴, which is arranged by means of steps constructed and arranged in the ordinary manner. The casting B is arranged 55 within the upright frame A and is pivotally mounted between the uprights A², said casting having trunnions B', which are journaled in bearings B², secured upon the inner faces of the uprights A². This casting B has a longitudinal tubular portion B³, the bore of the rear end being of greater diameter than the bore of the forward end. This tubular portion does not extend entirely to the forward end of the casting B, but stops short of said 60 forward end, so that the said casting projects beyond the said tubular portion upon opposite sides, as most clearly indicated at B⁴ in Fig. 6, the purpose of which will appear hereinafter. A cylinder-rod C is arranged in the 65 tubular portion B³ and carries a nut C' upon its rear end, and surrounding the rear portion of the rod and within the enlarged portion of the bore of the tubular member is a spiral spring C², the purpose of which is to normally 70 hold the rod within the tubular member B³. The outer end of the rod C is reduced, as shown at C³ in Fig. 7, and said reduced portion being provided with a rib C⁴, and secured to this reduced end is one member of an essentially U-shaped arm D, said member being cut away upon the under side, as shown at D', to receive the rib or shoulder portion C⁴ of the rod C. A clip-plate D² embraces the reduced end C³ and securely fastens the 75 U-shaped arm to the outer or forward end of the rod, and it will be noted that this member of the U-shaped arm rests against the forward end of the tubular member B³ and upon the projecting portion B⁴ of the casting and will 80 therefore be held in a horizontal position so long as the casting is held in such position. The free member of the U-shaped arm is longer than the member connected to the rib C and upon its outer side is provided with a 85 spring-finger E, the purpose of which will appear hereinafter. An angular gripping-arm 90

F is pivotally connected to the U-shaped arm and preferably at the point where the said U-shaped arm is connected to the rod C, said lever F being of such shape that one portion thereof will extend across the U-shaped arm, while the other portion thereof will be in alinement with that member to which it is pivoted, and in order to hold the gripping-arm F in either of these adjusted positions I 10 employ a spring F', which surrounds the pivoted pole F² and bears upon the said gripping-arm, said spring being held in place by the nut or washer F³.

An arm G is hinged to the top A³ of the frame A, said arm carrying a weight G' at its lower end and a T-shaped head G² at its upper end. When a mail-bag is to be held, the arm G is pulled down to a horizontal position and the top ring H of the mail-bag H' is slipped 15 over one end of the T-shaped head G². The casting B is swung up to a horizontal position, and the lower ring H² of the mail-bag is brought into engagement with finger E. The gripping-arm F will be arranged in the position 20 shown in Figs. 1 and 3. When the train appears, the hook I carried by the car is thrown out, so as to grip the mail-bag, and as the car passes on it is obvious that the bag will be pulled away from the holder, and the casting B will then drop, and the weight G' 25 of the arm G will cause the said arm to swing to a vertical position. At the same time that a bag is taken from the arms G and D a bag may be delivered into the U-shaped arm from 30 the train, and if such be the case that portion of the gripping-arm F which extends across the U-shaped arm is thrown around in alinement with the member of the arm and the other end of the gripping-arm is thrown across the 35 U-shaped arm, thereby gripping the bag thrown into the U-shaped arm, and in order to provide for delivering a bag to the holder at the same time that one is caught up by 40 the train I provide the hook I' with a spring-finger K, similar in construction to the finger E and which is adapted to receive the upper ring L of the bag L'. The lower ring L² 45 is adapted to fit upon the T-shaped head M of the bar M', pivoted to the plate M², which is adapted to be secured to the sill of the car-door. A lever N is also pivoted upon said 50 plate, said lever having a T-shaped lug N', which is adapted to fit beneath the bar M' when said bar is thrown downwardly, as indicated in dotted lines Fig. 1 and full lines in Fig. 10. This lever N is also provided with a 55 foot-piece N², and by pressing upon said foot-piece the lever N can be drawn downwardly, throwing the bar M' back to its normal position after the mail-bag has been drawn therefrom. The bar M' is provided with a T-shaped 60 head, so that it can be used when the train is moving in either direction, and the arm G is provided with a T-shaped head G² for the 65 same purpose. The U-shaped arm D is reversible, so that it can be used in connection with trains moving in the same direction, and

in order to reverse the arm it is only necessary to pull upon the rod C until the member of the U-shaped arm clears the projection B⁴ 70. The arm is then reversed and the spring will immediately return the rod, together with the arm, to its normal position—that is, against the tubular portion B³ and resting upon the projections B⁴. 75

It will thus be seen that I provide a simple, efficient, and durable construction whereby a mail-bag can be held in the proper position for being delivered to a train and at the same time the said bag is taken up by the train another mail-bag can be delivered to the holder from the train. 80

While I have shown the ordinary form of hook upon the car, I desire it understood that my improved form of casting may be readily applied to the door-framing of the cars without materially altering the construction thereof; further, by simply providing the hooks now in use with the spring-finger the said hooks may be satisfactorily used in connection with my improvement. 85 90

Having thus fully described my invention, what I claim as new, and desire to secure by Letters Patent of the United States, is—

1. The combination with a frame of a weighted arm having a T-shaped head, a casting pivoted to the frame and having a reversible U-shaped arm connected therewith, spring-actuated means for holding the said arm in its proper position, a spring-finger carried by the free member of the U-shaped arm and an angular gripping-arm arranged upon the other member, together with means for holding the said gripping-arm in its proper position as specified. 95 100 105

2. The combination with the frame, of the weighted arm, the pivoted casting and the reversible U-shaped arm, said arm being provided with means for holding a mail-bag, and the swinging hook adapted to be carried by a mail-car, a hinged bar having a T-shaped head and a finger arranged upon the swinging bar, as and for the purpose specified. 110

3. The combination with the swinging hook of the spring-finger arranged thereon, a hinged bar having a T-shaped head, a pivoted lever having a lug adapted to engage the hinged bar for the purpose specified. 115

4. The combination with the frame, of the casting having laterally-projecting trunnions, and a longitudinally-arranged tubular portion, the rod arranged in said tubular portion, the nut arranged upon the rear end, the spring arranged within the tubular portion and bearing against the said nut, the U-shaped frame rigidly connected to the forward end of the rod, the spring-finger carried by the free member of the U-shaped frame and a gripping-arm pivotally mounted upon the other member, substantially as described. 120 125 130 135

5. A mail-bag catcher and deliverer comprising a frame, an arm pivoted thereto, a revolute shaft carried by said arm, and a U-shaped arm secured to the outer end of the

shaft adapted to hold one end of a bag to be delivered to a car, and to receive a bag delivered from a car.

6. A mail-bag catcher and deliverer comprising a stationary frame, an arm pivoted thereto, a U-shaped arm adapted to hold one end of a mail-bag reversibly secured to the arm, an angular gripping-arm pivoted to one

member of the U-shaped arm and a spring-finger carried by the other member of the U-shaped arm, substantially as specified.
